CLAIM

The ornamental design for a housing for an optical fiber distribution module, substantially as shown and described.

DESCRIPTION

FIG. 1 is a top, front and left side perspective view of a housing for an optical fiber distribution module showing our new design;

FIG. 2 is top plan view thereof;

FIG. 3 is a left side elevation view thereof;

FIG. 4 is a right side elevation view thereof;

FIG. 5 is a front elevation view thereof; and,

FIG. 6 is a rear elevation view thereof.
